CLAIM

The ornamental design for a combined hooded jacket with vest, as shown and described.

DESCRIPTION

FIG. 1 is a front perspective view of a combined hooded jacket with vest showing my new design;

FIG. 2 is a front elevational view thereof;

FIG. 3 is a rear elevational view thereof;

FIG. 4 is a front perspective view thereof with the hood and sleeves rolled up;

FIG. 5 is a front elevational view thereof of that shown in FIG. 4;

FIG. 6 is a rear elevational view thereof of that shown in FIG. 4;

FIG. 7 is a front perspective view thereof of a second embodiment of that shown in FIG. 1;

FIG. 8 is a front elevational view thereof of that shown in FIG. 7; and,

FIG. 9 is a rear elevational view thereof of that shown in FIG. 7.
